US00D979330S

(12) **United States Design Patent** (10) Patent No.: **US D979,330 S**
McConnell et al. (45) Date of Patent: **** Feb. 28, 2023**

(54) **BLENDER JAR**

- (71) Applicant: **WHIRLPOOL CORPORATION**, Benton Harbor, MI (US)
- (72) Inventors: **John W. McConnell**, St. Joseph, MI (US); **Brandon T. Mock**, St. Joseph, MI (US); **Aaron McNabb Evans**, St. Joseph, MI (US)
- (73) Assignee: **Whirlpool Corporation**, Benton Harbor, MI (US)
- (**) Term: **15 Years**
- (21) Appl. No.: **29/848,146**
- (22) Filed: **Jul. 29, 2022**

Related U.S. Application Data

- (63) Continuation of application No. 29/816,167, filed on Nov. 19, 2021, now Pat. No. Des. 959,911, which is (Continued)

(57) **CLAIM**

We claim the ornamental design for a blender jar, as shown and described.

DESCRIPTION

FIG. 1 is a first side perspective view of a blender jar of the present disclosure;
FIG. 2 is a second side perspective view of the blender jar of FIG. 1;
FIG. 3 is a front perspective view of the blender jar of FIG. 1;
FIG. 4 is a rear perspective view of the blender jar of FIG. 1;
FIG. 5 is a first side elevational view of the blender jar of FIG. 1;
FIG. 6 is a second side elevational view of the blender jar of FIG. 1;
FIG. 7 is a third side elevational view of the blender jar of FIG. 1;
FIG. 8 is a fourth side elevational view of the blender jar of FIG. 1;
FIG. 9 is a top plan view of the blender jar of FIG. 1; and, FIG. 10 is a bottom plan view of the blender jar of FIG. 1. The broken lines depict portions of the article that form no part of the claimed design.

1 Claim, 10 Drawing Sheets

Related U.S. Application Data

a continuation of application No. 29/781,150, filed on Apr. 28, 2021, now Pat. No. Des. 938,228, which is a continuation of application No. 29/718,727, filed on Dec. 27, 2019, now Pat. No. Des. 920,045.
